(57) **CLAIM**

The ornamental design for a set of balustrade end parts of a passenger conveyor, as shown and described.

DESCRIPTION

FIG. 1 is a perspective view of a right hand of the set of balustrade end parts of a passenger conveyor as shown in FIG. 8, according to an embodiment of the present invention; FIG. 2 is a front view thereof; FIG. 3 is a left side view thereof; FIG. 4 is a right side view thereof; FIG. 5 is a top view thereof; FIG. 6 is a bottom view thereof; FIG. 7 is a front view of a left hand of the set of balustrade end parts of a passenger conveyor as shown in FIG. 8, according to an embodiment of the present invention, the left hand end part being a mirror image to the right hand end part; and, FIG. 8 is a perspective view of the set of balustrade end parts of a passenger conveyor according to the present invention. The right hand and left hand end parts are shown separately in FIGS. 1 through 7 for convenience of illustration.

The broken lines in the foregoing Figures are for the purpose of illustrating environmental structure and form no part of the claimed design.
